UNITED STATES PATENT OFFICE.

HUBBARD F. HURD, OF TROY, NEW YORK, ASSIGNOR TO CLUETT, PEABODY & CO., INC.,
OF TROY, NEW YORK, A CORPORATION OF NEW YORK.

DESIGN FOR A FOLD-COLLAR.

48,000.

Specification for Design.

Patented Oct. 19, 1915.

Application filed July 25, 1914. Serial No. 853,170. Term of patent 3½ years.

To all whom it may concern:

Be it known that I, HUBBARD F. HURD, a citizen of the United States, residing at Troy, in the county of Rensselaer and State of New York, have invented a new, original, and ornamental Design for Fold-Collars, of which the following is a specification, reference being had to the accompanying drawing, forming part thereof.

The figure is a front view of a fold-collar showing my design.

The fine parallel shade-lines on the drawing are intended to indicate a striped material.

I claim:

The ornamental design for a fold-collar as shown and described.

HUBBARD F. HURD.
